UNITED STATES PATENT OFFICE.

CHARLES CLARKE PUCKETTE, OF SALFORD, ENGLAND, ASSIGNOR OF ONE-HALF TO CONNER MAGNETO & IGNITION, LIMITED, OF STOKE, COVENTRY, ENGLAND.

IGNITION SYSTEM FOR INTERNAL-COMBUSTION ENGINES.

Application filed August 9, 1921. Serial No. 490,933.

(GRANTED UNDER THE PROVISIONS OF THE ACT OF MARCH 3, 1921, 41 STAT. L., 1313.)

To all whom it may concern:

Be it known that I, CHARLES CLARKE PUCKETTE, a citizen of the United States of America, residing at Peel Works, Adelphi, 5 Salford, Lancashire, England, have invented certain new and useful Improvements in an Ignition System for Internal-Combustion Engines (for which I have filed application in England May 23, 1919, Patent No. 10 143,047), of which the following is a specification, such as will enable others skilled in the art to which it appertains to make and use the same.

This invention relates to an improved 15 unispark ignition system of the separately excited induction coil type such as that employing a battery or an accumulator or a dynamo as the primary source of current.

Battery or the like systems in which the 20 single spark method of igniting the explosive gases in internal combustion engines is employed, usually include an induction coil whose primary winding is of comparatively low self induction, a timing interrupter which breaks the primary circuit at 25 certain intervals during the rotation of the engine countershaft, and in the case of a multi cylinder engine a distributor associated with the secondary circuit. The distributor and interrupter are generally 30 mounted as one unit.

The great disadvantage of such unispark systems employing a battery or other source of low voltage to suit the primary, is that 35 at the very high speeds the duration of the contact of the timer electrodes is not sufficient to enable the core of the induction coil to build up a maximum field before interruption of the primary circuit is effected, 40 and this results in a weak secondary spark, that is unless the resistance and self induction of the primary be made abnormally low.

If in order to assist the field of the core 45 to build up sufficiently at the high speeds, that is, when the contact between the electrodes of the timer is of short duration, a comparatively high voltage be used, say 6 to 12 volts, it is necessary to incorporate in 50 the circuit, a limiting or regulating resistance, otherwise at low speeds, or should the engine stop with the ignition control switch closed, excess currents might flow

through the primary circuit to the detriment of the induction coil and possibly to the 55 battery or accumulator, and such heavy currents flowing at low engine speeds would cause severe sparking at the contacts of the timer, shortening their life.

The object of the present invention is to 60 obviate these difficulties and the manner in which I carry the invention into practice is now set forth, and is illustrated by the accompanying diagrammatic drawings, where Fig. 1 is a diagrammatic showing of the 65 ignition system, and Fig. 2 shows a modified construction of the core, shading coil and switch contacts. A represents the core of the induction coil, B the primary winding and C the secondary winding. The 70 contacts of the timing contact breaker or interrupter which is actuated by the engine are indicated by D, D' the condenser by E and the battery by F.

The induction coil may have its core A 75 provided with a primary winding B of the usual low resistance and small inductance, but I arrange according to my invention that one end of the core is surrounded by a shading or lagging coil G and at this end 80 of the core A, I place the armature H of a contact breaker whose contacts J, J' are bridged by a resistance K which in my improved system takes place of the aforesaid 85 current limiting or regulating resistance.

By the action of the shading coil G a time lag between the maximum magnetic saturation in the part of the core A surrounded by the primary winding B, and the magnetic saturation in the shaded pole tip A' is provided, so that at the low speeds when the 90 duration of the contact between the electrodes of the timer or engine contacts D, D', is long and consequently the primary current has sufficient time in which to attain 95 its maximum, the magnetism builds up through the shading coil sufficiently to attract the armature H of the contact breaker, which moving over, opens the contacts J J' and includes the resistance K in series with 100 the timer contacts D, D', the primary winding B and the battery F or equivalent. This resistance may be such as, say, with 6 to 12 volts, to limit the current in the primary winding to that required to produce 105 the necessary magnetic excitation of the core,

without unduly wasting energy in the primary winding.

At high speeds, when the duration of contact between the electrodes D D' of the timer is much reduced, the flux in the induction coil core A, while able to build up to its maximum in the portion of the core embraced by the primary winding B, never reaches anywhere its maximum in the end 10 A' of the core shielded by the lagging coil; therefore the armature H of the contact breaker is not attracted and the contacts J J' remain closed, consequently the circuit is then operating with minimum resistance 15 and the current will only be limited by the self induction of the primary winding and the resistance of the circuit as a whole.

The shading or lagging coil G could either be simply a band of copper or aluminium, 20 or it may be cast around the laminated core in aluminium or suitable metal. If desired, it may be of suitable dimensions to form a base on which parts may be mounted, and Fig. 2 illustrates a convenient method of so 25 supporting the armature H and contacts J J' on the shading coil G'; by enlarging dimensions of this coil the parts G² will carry the armature spring H' at one side and the contact member J' at the other side, 30 the parts being suitably insulated as shown.

What I claim is:—

1. An electric unispark ignition system having an induction coil, a primary winding therefor having a shunt circuit path including resistance, a lagging coil for one end of the induction coil to provide a time lag between the magnetic saturations of the respective ends of the coil, and means controlled by the magnetic saturation of that 40 end of the induction coil having the lagging coil to control the resistance shunt circuit of the primary circuit.

2. An electric unispark ignition system, having an induction coil, a primary circuit 45 therefor, a shunt path for said primary circuit including resistance, and means for controlling the shunt path of the primary circuit, said means providing a time lag between the magnetic saturations of the respective ends of the coil.

3. An electric unispark ignition system, having an induction coil, a primary circuit therefor, a shunt path for said primary circuit including resistance, a lagging coil for 55 one end of the induction coil to prevent magnetic saturation of that end of the coil simultaneously with the magnetic saturation of the opposite end, and means controlled by the magnetic saturation of that end of 60 the induction coil provided with the lagging

coil for controlling the shunt path of the primary circuit.

4. An electric unispark ignition system, having an induction coil, a primary winding therefor, means for delaying the time 65 period of the magnetic saturation of one end of the coil as compared with the other end of such coil, and means for introducing a resistance in the primary circuit under full magnetic saturation of the coil within 70 the predetermined limit.

5. An electric unispark ignition system including an induction coil, a primary circuit, and means for varying the resistance of the primary circuit in accordance with 75 the relative time period of the magnetic saturation of the respective ends of the coil.

6. An electric unispark ignition system including an induction coil, a primary winding therefor, a shunt circuit including resistance for said primary winding, a lagging coil arranged at one end of the induction coil, and a switch controlled by said end of the induction coil for controlling the shunt circuit. 80

7. An electric unispark ignition system having an induction coil, the iron core of which is provided at one end with a shading or lagging coil, consisting of short-circuited turns. 90

8. An electric unispark ignition system having an induction coil, the iron core of which is provided at one end with a shading or lagging coil for producing a time lag in the magnetic field around the end of the 95 core shielded by the said lagging coil.

9. An electric unispark ignition system, including an induction coil, a lagging coil provided at one end of the induction coil for producing a time lag in the magnetic field 100 around that end of the coil, a resistance circuit, and contacts for controlling said circuit in connection with the primary winding of the induction coil, said lagging coil controlling the operation of said contacts in 105 accordance with the magnetic saturation of that end of the induction coil provided with the lagging coil.

10. An electric unispark ignition system having an induction coil, the primary winding therefor having a shunt circuit path including resistance and a contact control for such circuit, and a shading or lagging coil fixed on the core of said induction coil and carrying the contact control for such shunt 115 circuit.

In witness whereof I have hereunto set my hand.

CHARLES CLARKE PUCKETTE.
